(57) **CLAIM**

The ornamental design for a putter head striking face, as shown and described.

DESCRIPTION

FIG. 1 is a perspective view of a putter head striking face showing my new design,

FIG. 2 is an enlarged fragmented perspective view taken on circle 2 of FIG. 1,

FIG. 3 is a front view of FIG. 1,

FIG. 4 is a top view of FIG. 1,

FIG. 5 is a bottom view of FIG. 1,

FIG. 6 is a right-side view of FIG. 1,

FIG. 7 is a left-side view of FIG. 1; and,

FIG. 8 is a back view of FIG. 1.

In the drawings the broken lines depict portions of the invention that form no part of the claimed design.

1 Claim, 8 Drawing Sheets
